UNITED STATES PATENT OFFICE.

GUSTAF ALMEN, OF NORWICH, CONNECTICUT.

GAME-TABLE.

1,098,701.

Specification of Letters Patent. Patented June 2, 1914.

Application filed May 2, 1913. Serial No. 765,031.

To all whom it may concern:

Be it known that I, GUSTAF ALMEN, a citizen of Sweden, residing at Norwich, in the county of New London and State of Connecticut, have invented certain new and useful Improvements in Game-Tables, of which the following is a specification.

This invention relates to improvements in game tables and more particularly to such tables upon which games are played with balls and pins, somewhat after the manner of ten-pins. Its object is to produce a table of this class in which the pins after being knocked down by the balls may be ingeniously reset through the medium of their connection to spring-pressed movable posts adjacent the far end of the table which are actuated by a plurality of lug-bearing disks mounted upon a common shaft rotated by a crank arm. A ball return is also a feature of the table.

With the foregoing and other objects in view the invention consists in the combination and arrangement of parts to be herein-after fully described in the following specification, pointed out in the claims and illustrated in the accompanying drawings which form a part of said specification and in which—

Figure 1 is a plan of my game table. Fig. 2 is a longitudinal section in side elevation. Fig. 3 is an end view of the pin resetting mechanism. Fig. 4 is a front view of the same.

Like reference characters indicate corresponding parts throughout the several views.

My table comprises a level ball race 1 supported at one end upon suitable posts 2, resting upon the floor or other supporting surface and at the other end merging into inclined ways 3, 3 which merge into lateral inclined chutes 4, 4 that extend to the far end of the ball race. The end of the table adjacent the ways 3, 3 is provided with a plurality of apertures 5 over each of which a pin 6 is disposed that is connected by a flexible member 7 passing through the table aperture and over a pulley 8 secured to the under surface of the ball race to one of the pulleys 9 disposed upon supports 10 secured in the floor at the far end of the table; from the pulleys 10 the flexible members 7 extend to and about pulleys 11 disposed upon shafts 12, 12 journaled in bearings secured to one of the uprights 13, 13 disposed upon the floor adjacent the table end. From the pul-

leys 11 the flexible members 7 are extended and connected to posts 14 extending through apertures in a shelf 15 connecting the said uprights; posts 14 being retained in position by springs 16 which are fastened to and encircle them, the lower end of said springs resting upon the shelf 15. Each post 14 is provided with a tooth 17, no two of said teeth being disposed in the same horizontal plane.

The upper ends of the uprights 13, 13 are connected by a crank shaft 18 provided with a handle 19 and upon said shaft a plurality of disks 20, one disk for each post, are mounted; each of said disks being formed with a plurality of lugs 21 upon its periphery which, as the crank shaft is rotated, are adapted for engagement with the teeth 17.

Operation: A ball 22 is rolled along the ball race from the end remote from the ways 3, 3 toward the pins 6. A pin struck by the ball will be knocked down causing the flexible member 7 to exert a slight "pull" on the post 14 connected to said pin against the tension of the spring 16; the ball will roll off the race over one of the ways 3 and into the chute 4 and gravitate to its starting point. The upset pin is reset in the following manner: Oscillation of the crank shaft 18 will cause one of the lugs 21 of one of the disks 20 to engage a tooth 17 of the adjacent post 14 thus raising said post partially out of its seat and causing the flexible member 7 to exert a strain upon the pin 6 again disposing it in an upright position at right angles to the ball race.

What is claimed is:—

1. In a game table, a ball race, inclined chutes adjacent said ball race, ways connecting said ball race and inclined chutes, pins disposed upon one end of said ball race, connected uprights disposed adjacent the opposite end of said ball race, spring-pressed posts carried by said upright connections, flexible means connecting said spring-pressed posts and the aforesaid pins, a tooth carried by each of said spring-pressed posts, a crank shaft journaled in said uprights and means carried by said crank shaft for engagement with said teeth whereby said spring pressed posts may be moved in their seats to cause pins to assume an upright position.

2. In a game table, a ball race apertured at one end, inclined chutes adjacent said ball race, ways connecting said ball race and

inclined troughs, pins disposed upon said race over the apertures therein, uprights adjacent the end of said ball race remote from said pins, a shelf connecting said uprights, 5 spring-pressed posts carried by said shelf, flexible means connecting said pins and spring-pressed posts and extending through the apertured portions of said ball race, a tooth carried by each of said spring-pressed 10 posts, no two teeth being disposed in the same horizontal plane, a crank shaft mount-

ed in said uprights and disks mounted upon said crank shaft provided with peripheral lugs for engagement with the said teeth, singly, as said crank shaft is rotated.

15

In testimony that I claim the foregoing as my own I have hereto affixed my signature in the presence of two subscribing witnesses.

GUSTAF ALMEN.
